(57) **CLAIM**

The ornamental design for a load transfer key, as shown and described.

DESCRIPTION

1. Load transfer key

1.1 : Perspective

1.2 : Perspective

1.3 : Front

1.4 : Right

1.5 : Top

1.6 : Bottom

The back view is omitted because it is a mirror image of the front view; the left side view is omitted because it is identical to the right side view; the load transfer key is a member for preventing one of the joints to be connected from coming off the other.
